CABINET WITH MULTIPLE DRAWERS AND COMPARTMENTS

William Joseph Carr, Gardner, Mass., assignor to Heywood-Wakefield Company, Gardner, Mass., a corporation of Massachusetts

Application April 28, 1950, Serial No. 9,529

Term of patent 7 years

(Cl. D33—19)

To all whom it may concern:

Be it known that I, William Joseph Carr, a citizen of the United States, residing at Gardner, in the county of Worcester and Commonwealth of Massachusetts, have invented a new, original, and ornamental Design for a Cabinet With Multiple Drawers and Compartments, of which the following is a specification, reference being had to the accompanying drawing, forming part thereof, in which:

Fig. 1 is a view in perspective of a cabinet with multiple drawers and compartments, showing my new design.

Fig. 2 is a view in front elevation of the cabinet shown in Fig. 1.

Fig. 3 is a view in end elevation of the cabinet shown in Fig. 1, with a portion of the cabinet in vertical section along the line 3—3 of Fig. 2, looking in the direction of the arrows.

Fig. 4 is a fragmentary sectional view along the line 4—4 of Fig. 2 looking in the direction of the arrows.

I claim:

The ornamental design for a cabinet with multiple drawers and compartments, substantially as shown.

WILLIAM JOSEPH CARR.
